UNITED STATES PATENT OFFICE.

BENJAMIN TRIVUS, OF NEW YORK, N. Y.

CLOCK.

1,193,315.

Specification of Letters Patent.

Patented Aug. 1, 1916.

Application filed October 24, 1912. Serial No. 727,522.

To all whom it may concern:

Be it known that I, BENJAMIN TRIVUS, a citizen of the United States, and a resident of the city of New York, borough of Brooklyn, in the county of Kings and State of New York, have invented a new and Improved Clock, of which the following is a full, clear, and exact description.

My invention relates to an improvement 10 in clocks, and the object thereof is to provide a time indicating device which is so constructed as to strike not only hours, but subdivisions as well, so that any one in the vicinity of the clock can inform himself as to the hour and the minute at any time during 15 the day or night, whether he can see the dial over which the hour and minute hands move or not.

I attain the above objects by means of a 20 construction which includes a sound-producing device such as a bell or gong, and suitably operated members such as clappers or hammers, which strike the same and set it in vibration; and these members are so 25 controlled as to be positive in their action and regulated so as to be moved in synchronism with the hour hand and the minute hand, so as to strike the bell or gong a suitable 30 number of times corresponding with the positions of the hour hand and the minute hand, respectively, the clappers being of different material so as to produce sounds which enable the hearer to distinguish them from each other.

I may also provide means in the shape 35 of electrically actuated circuits including illuminating devices which are so connected that they can be energized whenever the hour or minute is being struck, and these 40 illuminating devices will indicate the character of the signal which my invention is giving; that is to say, there will be a lamp which will light up when the hour is struck, and another lamp, preferably of a different 45 color, which will be lighted when the sound-producing device is indicating the particular sub-division of the same.

These and other objects and features of my invention will be more fully set forth in 50 the following specification taken in connection with the accompanying drawings whereon—

Figure 1 is a front view of a mechanism embodying my invention; Fig. 2 is a side elevation viewed from the left of Fig. 1; Fig. 55 3 is a front elevation similar to Fig. 1, with

part of the framework broken away to show the gearing more fully; Fig. 4 is an enlarged sectional view taken substantially on a vertical plane passing centrally through Fig. 2, to show the controlling devices for the striking members; Fig. 5 is a top plan of the controlling mechanism for the striking members; Figs. 6 and 7 are detail views showing the parts of the controlling mechanism in two different positions. Fig. 8 is a plan view of another element forming part of the controlling mechanism; Fig. 9 is a view of one of the controlling hanger bars which allow the striking members to come into play at the right moment; Fig. 10 is a view of a detail, showing how the hanger bars are pivotally suspended; Fig. 11 is a view of a modification of part of these hanger bars; Fig. 12 is a view showing a modified form of hanger bar; Fig. 13 is a view of an attachment whereby I may add a visual indicator to my clock, controlling the same by the passage of electric current; Fig. 14 is a top plan of the part shown in Fig. 13; Fig. 15 is a vertical sectional view of a modification; Fig. 16 is a detail of the form shown in Fig. 15; Fig. 17 is a view of a third modification; and Figs. 18, 19 and 20 are views of details used in the form shown in Fig. 15.

In the embodiment of my invention illustrated I employ the usual framework shown at 1, in which are mounted the usual gear wheels by means of which the hands of a 90 clock are turned. This frame work supports a bell or gong 2, which is located in position to be struck by a pair of hammers or clappers 3 and 4, the former indicating the minutes and the latter the hours. These 95 members are secured at the ends of arms 5 which are controlled in their action so as to engage the gong 2 at the proper instant and the proper number of times, according to the hour and the minute which are to be 100 struck, by an arrangement of controlling devices fully described later. The hammers 3 and 4 are made of different substances so as to produce distinguishing 105 sounds. Concentric with the bell 2 and inside of the same is a main spring 6 which has one end anchored at 7 and gives motion to a main shaft 8. This main shaft 8 carries a large gear 9 which meshes with a pinion 10 on shaft 11, see Fig. 1, and this latter shaft carries a large gear 12. This gear 12 transmits motion to a small pinion 13

on a shaft 14 carrying a gear wheel 15. The gear wheel engages a pinion 16 on a shaft 17 and thus turns a fourth large gear 18 mounted on this last-named shaft. 5 The gear 18 turns a pinion 19, see Fig. 2, on a shaft 20, the outer end of which projects through a bearing in a bracket 21, and carries an escapement wheel 22 having inclined teeth 23. The gear 12 also engages 10 a pinion 24 mounted on a central shaft 25 which projects through the front of the frame and carries the minute hand of the clock. The shaft 25 also carries another pinion 26 which meshes with a gear 27 on a 15 shaft 28. This gear 27 transmits motion to a pinion 29 which operates the controlling devices for the hammer 3. On the spindle 28 and turning therewith and with the gear 17 is another pinion 30, see Fig. 2, by 20 means of which motion is transmitted to a large gear wheel 31, which is rigidly mounted on sleeve 32. This sleeve projects out through the front of the casing and surrounds the shaft 25, and serves to transmit 25 motion to the hour hand. This sleeve turns at one-twelfth the same angular speed as the shaft 25, as is required in clocks of this type. The pinion 30 also meshes with a gear 33, which actuates the controlling devices for the hammer 4.

It will be seen in Fig. 2 of the drawings that the gears 12, 15 and 33 with their associated pinions are all located adjacent the front of the clock frame while the gears 26 35 and 27 with their associated pinions are located at the back of said frame. Furthermore, the gearing described will be so designed that the sleeve 32 will turn one-twelfth as fast as the shaft 25. The pinion 29 and the gear wheel 33 will be turned faster than said sleeve. The gear wheels 29 and 33 have surfaces which are engaged by springs 29', 33', see Fig. 4, on the frame to hold the gears against free movement. 40 The diameter of the pinion 29 will in practice be made equal to the diameter of the pinion 26, and the diameters of the gears 31 and 33 will likewise be equal. Furthermore, the gears 29 and 26 will have the same speed, 45 and the gears 31 and 33 the same speed. 50

The ratchet wheel 22 is controlled by means of an escapement device comprising a lever 34 having lugs 35 located at or near the center of the same and mounted by 55 means of perforations in these lugs to rock upon a pivot pin 36. This lever has its ends bent as shown in Fig. 1, and as it rocks each end will engage the inclined edges of the teeth 23 by turns, permitting the ratchet wheel to move intermittently in the usual way. This lever 34 will be rigid with a suspension bar 37 having a hook 38 at its lower end to carry a pendulum bob, and the bar 37 will be engaged by a spring 39 to 60 control its movements.

The end of the main shaft 8 may be squared or given some other polygonal shape, as shown at 40, and may be connected rigidly with the inner end of the spring and to the large gear 9 by means of a 70 ratchet 41, so as to enable the spring to be wound up without turning the wheel, and enable the unwinding movement of the spring, causing the shaft to be turned in the opposite direction to carry the ratchet wheel 75 and the large gear 9 with it.

The hammer bars 5 are actuated by means of arms 42 secured to pivoted spindles 43. These hammer bars are made rigid with these pivoted spindles, and the arms 42 are 80 engaged by the teeth of the gear 18, as shown in Fig. 3, the gear rotating counter-clockwise, and it will be evident that each tooth lifts the free ends of the bars 42. As the arms slip past the teeth engaging the same 85 the hammer bar will be dropped and the hammer at the end will strike the bell 2. The spindles 43 will also be provided with threaded projections on which are screwed adjustable counterweights 44. These counterweights regulate the force with which the hammers 3 and 4 impinge upon the bell 2. An arm 5', see Fig. 3, with a pin at its end can be employed to lift the hammers 3 and 4 to throw them out of operation, this arm 90 being actuated by a knob or projection at the back of the clock.

At the top of the frame 1 and extending transversely thereof at both the front and back of the same is arranged a pair of uprights 45, each of which has an inwardly-extending lug to receive a mounting device 46. This mounting device pivotally supports a pair of yokes 47, each carrying a rigid downwardly-projecting lug 48. Each of the yokes is also provided with a counterweight 49, and secured to each lug 48 by means of a screw and slot connection to make the same adjustable is a hanger bar which has projections thereon to engage the 100 hammer bars 5 and prevent them from striking the bell 2, except at the right instant. The hanger bars are shown at 50 and 51, two at the front and two at the back of the frame, the front pair being associated 105 with the hammer 4 and the back pair with the hammer 3. The bars 50 and 51 are pivoted on the devices 46. The counterweights 49 are preferably in the form of milled nuts mounted upon threaded projections so as to be adjustable.

The hanger bars 51 are shorter than the bars 50. The bars 50 have notched ends 52, see Fig. 3, guided by pins 53. The hanger bars 51 have ring-shaped sections 54 concentric with the pinion 29. The said sections have projections 55 provided with bent-over ends 56, see Fig. 3, the parts 55 and 56 are in substantially horizontal planes. The bars 50 have projections 57. 110

The portions 56 and 57 for each pair of bars are preferably alined with each other. When the inner end of the portion 56 of one of the bars 51 contacts with the portion 57 of the associated bar 50, the adjacent hammer bar 5 will be arrested before the hammer strikes the bell 2. But when the bars 50 and 51 are swung apart to allow the associated hammer bar 5 to pass between 10 the hammer strikes the bell 2. The bars 50 and 51 are actuated by cams 58 on the shaft 17. These cams are best seen in Fig. 5 of the drawings. The bar 51 has an upturned end 59 on a projection 61. A 15 similar projection 61 is carried by the associated bar 50. The front bar 51 at the front of the clock frame has a projection 60 which extends upward and toward the front of the frame. These projections are engaged by 20 the cams 58 to move the one hanger bar to the rear and the other hanger bar to the front.

Each of the bars 50 has a perforation coaxial with the gear 29, and with a sleeve 62, 25 and a disk 63. At the edge of the disk 63 is a hook 64 pivotally mounted at 65. The hook 64 has a projection 66 and a projection 67 as is seen in Fig. 4. The hooks 64 are shaped as shown at 68, to form cam like 30 surfaces. The disks 63 each carry a pin 69 which extend inward, as shown in Fig. 4. Each hook 64 has a projection 66' adjacent the pivot 65 for limiting the upward movement of the hooks 64.

35 The upper end of each hanger bar 50 as best seen in Fig. 9 of the drawings carries a spring 70, having ends 72 which pass through openings in each bar 50 and engage the disk 63, and force it against the end 40 flange of the sleeve 62. Between the ends of this disk is a shoulder which rests against one face of the bar 50 and adjacent the shoulder, and at the opposite face of the bar 50 is a groove or recess 73 which receives a 45 spring 74 also secured to the bar 50. This shoulder and this spring 74 hold the bar and the sleeve 62 together. A screw 71 holds the spring 70 in place.

The bars 50 each carry a spring 75 which 50 extends upward along the lower edge of the projection 61, and is bent in position to be engaged by the cam 58, as shown in Fig. 5. This down-bent portion of the spring 75 is engaged by a screw 76 to regulate 55 the position thereof. If desired, the spring 75 can be omitted and the part 61 shaped to take its place.

The pinion 29, likewise the hub of the gear 33, has projecting bosses 77 which are 60 hollow, and through the gear 29 and the hub of the gear 33 pass rivets forming journals on which the gears 29 and 33 rotate. The hollow bosses 77 form friction mounts 65 for sleeves 78. At the outer ends of sleeves 78 are mounted disks 79 which have slotted

projections 80 through which project the pins 69 carried by the lower ends of the disks 63. From this construction it will be seen that when the gears 29 and 33 are turned, carrying the sleeves 78 with them, 75 the disks 79 will be turned also, and through the pins 69 the disks 63 will be moved on the bushings 62. This movement will change the angular position of the hooks 64.

The rivets which extend through the front 75 and back of the frame 1, forming the journals for the gears 29 and 33, have reduced screw-threaded inner ends shown at 81, and upon these projections are screwed sleeves 82. These sleeves have perforations in their 80 ends and serve as bearings supporting a spindle 83 having journals 84 which pass through the apertures in the ends of the sleeves 82. The spindle 83 carries an actuating pinion 85 which is engaged by the 85 gear 18, see Figs. 3 and 5. The sleeves 82 have heads to engage the ends of the hubs of the gear wheels 29 and 33 and hold these gear wheels in proper position. The spindle 83 also carries a pair of rigidly mounted 90 sleeves 86 on which are fixed disks 87 having recesses 88 as best seen in Fig. 8 of the drawings. On the sleeves 86 are also fixed plates 89, which are located adjacent the recesses 88.

95 The pivotally-mounted device shown at 46 for the yokes 47 is illustrated in full in Fig. 10. It comprises a screw 90 having screw-threaded engagement with one of the upright projections 45, and having a smooth 100 reduced end 91 on which one arm of one of the yokes 47 is journaled.

92 is a hollow bushing which has screw-threaded engagement with an aperture in the arm of the adjacent yoke, and has an 105 opening through its end which receives the projection 91. This construction is the same for each of the arms of the yokes 47 at the front and back of the frame 1, and it will be seen that the larger yokes swing upon 110 the projections 91 as journals, and the smaller yokes also swing upon the projections 91 as journals through the engagement therewith of the bushings 92. The parts 90 and 92 permit the adjustment of the 115 devices 46.

In operation, the main spring 6 will rotate the gearing so as to turn the sleeve 32 and the shaft 25 at the rate of twelve to one, to rotate the minute hand at the proper 120 relative speed. The operation of the spring 6 will be regulated by means of a pendulum and escapement in the usual way.

The cams 58, are located the proper distance apart, for engaging the projections 125 59 and 60 on the front and rear pair of hanger bars 50 and 51, to move these bars toward the front and back of the framework, respectively, as seen in Figs. 5 and 6 of the drawings. Normally, these bars will 130

occupy the position shown by the pair at the left of Fig. 4, the counterweights 49 being regulated to hold them in such location. In this position the portions 56 and 57 will prevent the hammers 3 and 4 from striking the bell 2, although the gear 18 moves the arms 42 to swing the bars 5 outward and allow them to drop back under the influence of their own weight, the portions 56 and 57 arresting these bars 5 before the hammers 3 reach the bell 2.

When the bars 50 and 51 are in position as shown at the right in Fig. 4, the corresponding cam 58 will move the bars to the right together and hold the same in such position until the said cam 58 passes the outer ends of the extensions 61. When these arms hang at rest the projection 66 on the catch 64 will be engaged by the edge of the ring 54 of the hanger bar 51 and swung away from the pin 69, as shown by the position of the corresponding catch at the left in Fig. 4. In this position the bent end 67 of the catch will clear the disk 87, so as to permit these two hanger bars 50 and 51 to be moved to the right as far as necessary. When the cam 58 releases the hanger bars they will tend to return to their original position by their own weight and the weights 49. It will be seen from Fig. 5 that the cam 58 releases the bar 51 first, and the bar 50 next. As the bar 51 starts on its return movement the inner edge of the ring-shaped section 54 of this bar will engage the inclined edge 68 of the hook 64 and lifts this hook to original position. The end 67 of the hook will now strike against the disk 87 and cause the return movement of the bar 50 to be arrested, even when the cam 58 moves past the element 75. The bars 50 and 51 therefore come into such relative position that the out-turned portions 56 and 57 remain apart long enough to permit the knob 4 to strike the bell a certain number of times to indicate the hour. The weights 49 on the hanger bars are properly designed with respect to the lower ends of the bars carrying the sleeves 62, the disks 63 and the hook 64.

Owing to the continuous rotation of the spindle 83 the disk 87 will be moved into such position as to bring the notch 88 (see Fig. 8) in position to permit the bent end 67 of the catch 64 to pass through the same. This will allow the bent end 67 to pass through the same. This will allow the hanger bar 50 to move back to its starting position, and the operation of striking the hour will then be completed, because the out-turned ends 56 and 57 carried at the lower ends of the bars 50 and 51 will now be together again and in position to stop the bar 5 carrying the knob 4 before the knob reaches the bell 2. The bar 51 is finally stopped by that part of the disk 79 which

carries the aperture receiving the pin 69, and when the bar 50 returns to original position the projection 66 will engage the ring 54 and move the hook 64 away from the disk 87 and disk 89. Through the motion of the gear 33, which is driven from the main spring, the boss 77 will be turned, and therewith the sleeve 78. This will cause the disk 79 to be rotated, and through its engagement with the pin 69 to turn the disk 63. Preferably the direction of rotation of the gear 85 and disks 87 and 89 is the same as the direction of rotation of the disks 79 and 63, but the disk 79, and consequently the disk 63, are rotating slower. The speed ratio of the disks 87 and 79 will be such as to increase the space of time which intervenes between the instant when the end 67 engages the disk 87, and the instant when, after passing through the adjacent recess 88, this end 67 slips over the edge of the disk 89. The last ring always takes place when the catch is against the disk 89, and the slipping of the upturned end 67 of the hook over the edge of this disk allows the hangers 50 and 51 to come together at their ends 56 and 57. For example, when the parts of the clock are in position to strike for the first time the hour of one, the disk 79 will be in such position as to hold the disk 63 so that the end 67 will not engage the disk 87 at all when the bar 50 returns, but will pass directly through the recess 88 and be stopped by the disk 89. The disk 89 will hold the ends of the bars 56 and 57 apart long enough to allow the knocker 4 to strike once, and after this single ring the end 67 slips off the radial edge of the disk 89 and further ringing is prevented. One hour later the disks 79 will have shifted the disk 63 so as to permit the end 67 to strike the disk 87 near the entering edge of the recess 88, so as to give the knob 4 a chance to strike once before the hook 67 passes into this recess, and once again before it slips off the edge of the disk 89. Thus the hour of two is indicated, and so on through the entire twelve hours, when the same operation is repeated.

The circumferential extent of the recess 88 is more than one-twelfth of the circumference, and the disk 89 for each of the disks 87 can be mounted on the element 86 so that it can be adjusted to bring its end into alignment with this recess in the proper position. The position of the elements in question is shown in Fig. 8.

The operation of the hanger bars 50 and 51 at the left in Fig. 4 is the same, only they regulate the knob 3 to strike the minutes. I preferably arrange the parts so that the knob 3 will strike once at five minutes after the hour; twice at ten minutes after the hour, and so on, so that the listener may ascertain by multiplying the number of

rings by the numeral five, the number of minutes that have intervened since the last hour.

As seen in Fig. 4 of the drawings, the disk 63 at the right in said figure, carrying the hook 64, revolves once in twelve hours, while the corresponding disk 63 at the left in said figure revolves once every hour. The notched disks 87 rotate at the same speed.

Both pairs of bars 50 and 51 are moved by the cams 58 an equal number of times per hour. The cams 58 move the pairs of bars alternately. The hour is struck first, and the minutes second, the hammer 4 striking the current hour for each minute during the hour, and the hammer 3 striking immediately afterward, to indicate that minute whose number is a multiple of five which is nearest to the present minute.

For convenience I have shown the disk 87 on Fig. 8 marked into twelve equal divisions, the mark indicating the beginning of the arc constituting the first division being located substantially at the edge of the recess, but near the point 2 above referred to, and the mark indicating the twelfth division being located in the recess 88 near the edge opposite the edge containing the point 1; that is to say, on the back plate 89. This is because the recess 88 is more than one-twelfth of the circumference, and if the first division begins at one edge of the recess, the last division will begin within the opposite edge of the recess.

Let us assume, for example, that, when the cam releases the hanger bars, allowing the same to swing apart, the inner edge of the ring 54 carried by the plate 51 engaging the inclined edge 68 of the catch to force it toward the spindle 83, the bent outer end of this catch will strike the disk 87 at the point marked 1', which practically coincides with the point 2. The disk rotating in the manner described will hold the hanger bars 40 and their ends 56 and 57 apart long enough to allow ten rings of the hammer to take place before the recess 88 comes in position to allow the catch to slip through it, and when this happens the eleventh ring will 45 be given when the catch engages the point marked 12 on the plate 89. The twelfth and last ring will occur when the catch, through the further movement of the disk and plate, is on the part 1'' on the plate 55 89, after which the catch slips off and allows the hanger bars 50 and 51 and their ends 56 and 57 to swing together. Further ringing is thus prevented. One minute later, when the hour of twelve is to be again 60 struck, the catch 64 will strike the point marked 2' on the disk 87, which is one-sixtieth of a division of the plate 87 distant from the point marked 1', and the twelfth ring will now occur when the catch 65 is on the point marked 2'' on the plate 89.

The catch 64 contacts with the disk 87 at the point 2', because the disk 79 has in the meantime shifted the disk 63 the required extent, moving it, as stated above, in the same direction as the direction of rotation 70 of the shaft 83 on which the disk 87 is mounted. In this way, the hour will be struck sixty times between the hours of twelve and one, and by the time the instant arrives when the knob 4 is to strike but once 75 to indicate that the hour of one has begun, the disk 63 will have been shifted to such an extent by the disk 79 that, when the cam releases the hanger bars 50 and 51, the end of the catch 64, owing to the relative position of the disk 87, will pass directly through the recess and strike upon the back plate 89 at the point 1''. Since, as above stated, the knob 4 will strike, owing to the associated 80 arm 42 being in position to slip off one of 85 the teeth of the gear 18 as soon as the arms are released the instant the ends 56 and 57 are swung apart, the ring to indicate that the hour of one has arrived will take place before the catch slips off the edge of the 90 back plate 89 adjacent the point marked 1''. One minute later, owing to the disk 79 continuing to shift the disk 63, the ends 67 of the catch will strike the back plate at the point 2'', to ring the hour of one the second time, 95 and this will take place sixty times until the knob 4 should strike the hour of 2. By this time the disk 79 will have shifted the disk 63 so as to make the catch engage the back plate about the point 12, and so on through the 100 entire twelve hours.

It will be seen that the gear 85 has twelve teeth, and that when the disk 87 arrests the catch by contacting with the same at the point marked 1', so as to hold the hanger 105 bars apart until the disk has moved into position to permit the catch to pass through the recess 88 and slip off the edge of the back plate 89, nearly a revolution of the disk and the gear 85 takes place. This gear, 110 as above described, intermeshes with the gear 18, and consequently when the gear 85 makes one complete revolution, the gear 18 moves twelve teeth to operate the bar 42, corresponding with the hammer 4, and 115 makes the hammer 4 give twelve rings. Similarly, when the hour of one is to be struck, the bars 50 and 51 are held apart through not more than one-twelfth of a revolution of the disk 87, which is to say, 120 one-twelfth of a revolution of the gear 85. Consequently, the gear 18 is moved so as to cause but one tooth to move the arm 42, and hence the knob 4 makes but one ring.

As stated above, every time the hour is 125 struck the first ring takes place the moment the ends 56 and 57 swing apart. This is because the arms 42 will be so related to the teeth of the gear 18 that the arm 42 operating the hammer 4, is released by one of the 130

teeth of the gear 18 the instant the ends 56 and 57 separate. This relation of the parts is necessary to prevent more than the necessary number of rings being given for each hour in the course of the hour; that is to say, while the disk 79 is shifting the disk 63 through the pin 69, so as to move the same into position to control the bars 50 and 51 in such a way as to cause the succeeding hour 5 to be properly struck when it arrives. For example, the first ring of the hour of twelve, when the hour of twelve is to be struck for the first time, takes place when the catch is on the point 1'. The first of the hour of 10 twelve, when the hour of twelve is struck the second time, takes place with the catch at the point 2', but during the entire hour, when the disk 63 is being shifted so that the catch contacts with the disk 87, successively 15 at sixty different points between the points marked 2 and 1 on the disk 87, no more than twelve rings should be given. The last ring of the hour of twelve when it is struck the first time takes place the first time at the 20 catch 1'', and the last ring of the hour of twelve when it is struck for the last time just before the time arrives for striking the hour of one, that is to say, the twelfth ring, when the hour of twelve is being struck for the 25 sixtieth time, will occur when the catch is near the point 12. From the point 12 to the opposite edge of the plate 89 near the circumference of the disk is not quite one-twelfth of the circumference of this disk, 30 and this means that the gear 85 will move not quite the space of one tooth to move the disk 87 and the plate 89 this distance. The gear 18 will not move said wheel 85 quite the space of one tooth, after the 35 twelfth and last ring of the hour of twelve. 40 Normally, the left disk 79 will turn once for each hour, and the disk 79 at the right once in twelve hours. Further, the cams 58 will turn once every two minutes, and the 45 wheel 85 and disks 87 two times in one minute. The cams 58 and gear 18 are mounted so as to be adjusted on the spindle carrying them. Preferably, also, the gear 18 will have forty-eight teeth and the gear 85 twelve 50 teeth, and the teeth on the other gear wheels will be in corresponding number, to secure the desired results. After one cam begins to act twelve teeth of the gear 18 pass before the next cam acts. 55 Referring to Figs. 13, 14 and 17, I employ a pair of blocks 94 mounted on pivots 95. To these blocks are secured the arms 42 and the hammer arms 5. Each of these blocks carries an insulating sleeve 96 secured thereto, and through each sleeve passes a metallic conductor 97. The sleeves are mounted at the front and back of the framework 1 at the top of the same, and there are four mercury cups 98, two in front and two 60 in back, the conductor 97 at the back bridg-

ing the rear pair and the conductor 97 in front bridging the front pair. These sleeves and the conductors are rocked as the arms 42 are moved by the gear 18, and they will be in level position, forming a path between the pairs of cups controlled by them as their respective arms slip off the cogs to enable the knobs 3 and 4 to strike the bell 2. The front pair of cups will form part of a circuit containing a red lamp, and the back 70 cups will form part of a circuit containing a white lamp. Consequently, when the hour strikes the red lamp will light, and when the minute strikes the white lamp will light up. The number of flashes will indicate the hour 75 and minutes. 80

In the form shown in Fig. 15 I employ a block 94 mounted upon any form of pivot shown at 95, this pivot to be carried by a bracket 45. 96 is an insulating sleeve, and 97 a conducting member bridging a pair of mercury cups located at the front and back of the frame 1. From one of these cups leads a conductor to a white lamp 99 which is in circuit with a battery 100, this battery being 90 connected to the bracket 45, which is preferably insulated from the framework at 45'. This insulating plate 45' carries a contact shown at 122', from which leads a wire 101 to a rotating hub or sleeve 102 carried upon 95 an insulating sleeve 103 on a journal 104. This journal carries a gear 29 actuated by the gear train shown in Figs 1 to 4 inclusive. On this hub is rigidly secured a plate 105 having a notched upper end forming a yoke 100 to receive screws 106. These screws have counterbored ends to receive the conical ends of a pin 107 which carries a projection 108. This pin is cut away on its lower side to form a square recess, and 109 is a bell-crank 105 lever pivoted on the plate 105 at 110. One arm of the bell-crank lever is engaged by a spring 111 anchored to the plate 105 by a screw 112, and at the other end of this arm is a projection 113, which engages the inner 110 end of the recess in the pin 107, to hold this pin in such position that the projection 108 will be vertical. This pin also has a horizontal projection 114.

The spindle 83 which carries the actuating 115 gear 85 is geared to a plate 115, to be turned therewith, but is insulated therefrom by a suitable bushing. This plate has a circumferential notch which is bridged by a segmental projection 116 carried at the end of an arm which is regulated by means of a screw 117, and pivoted to the plate 115 at 118. A spring 119 holds this arm against the regulating screw.

A third mercury cup shown at 120 is located between and beneath the cups 98, and in this cup dip the ends of a star wheel 121. This wheel may be carried by a shaft 122, which may be actuated at a constant speed by any mechanism and may carry the es- 120

capement wheel 23, if desired. As seen best in Fig. 16 of the drawings, the cup 120 is connected to a bracket 124 which may be raised or lowered by a regulating screw 125. The shaft 122 supports an insulating sleeve 123, so as to keep this shaft out of electrical contact with the framework. The outer end of this shaft with the sleeve thereon carries the wheels 19 and 23 as best seen in Fig. 15 of the drawings; and insulation 123' may be employed at this end also to keep the shaft out of electrical contact with the bracket 21. At the other end the shaft 122 will be in contact with the plate 122', but will be insulated from the back of the frame 1 by the plate 45'.

The hanger bar 51^a as shown in Fig. 15 of the drawings is similar to the hanger bar 51 shown in Fig. 3, with the extension 55 and end 56 omitted. It is mounted to depend from the pivot 45, and will normally be located so that its ring portion will be to the right of the pin 108. When in such position the pin 108 and the hanger bar will be insulated from each other by an insulating plate 51^b. When the cam 58 thus pushes this bar 51^a to the left it will move past the projection 108 and oscillate the conductor 97 and break the circuit between cups 98. When the cam releases the bar 51^a it will swing back, hitting against the projection 108 on the right side of the same, and thus an electrical contact will be established between the hanger and the pin 108, pressing against the right side of this hanger bar. Current will now flow from the battery through the lamp 99 between the mercury cups to the cup 120, and then through the wheel 121 and the shaft 122 which carries this wheel in contact with the same to the plate 122'. Thence it will flow by wire 101 to the hub 102, plate 105, pin 108, hanger bar 51^a, bracket 45, and thence by wire back to the battery 100. Consequently, the lamp will flash as often as one of the spokes of the wheel passes through the mercury in the cup 120.

Fig. 17 indicates a third modification, in which both the hammers and the lamps are used. In this form there are a pair of circuit-closing devices 126, rigid with the arms 5, and each of these circuit-closing devices touches a contact 127. From these contacts lead wires in multiple to a white lamp and a red lamp which are supplied with current from a battery or other source leading to a plate 128 which is in circuit with both the circuit closers 127. When the arm controlling the minute hammer is striking, the circuit through the white lamp will be closed intermittently, and when the other hammer is striking the hour the circuit through the red lamp will be closed intermittently. The moving contacts 126 and the fixed contacts 127 and the circuit connections therefor through the lamps and the battery will of

course be insulated from the framework in any suitable way; and so are the arms 5 and 42.

In practice, I prefer to start the ringing of the hour one at five minutes after one, so that there will be two rings of one, each indicating the hour and the minute, and so on with the other hours. I also prefer to make the ends 67 of the catches 64 beveled, so that the inner ends of the catches will be sharp and the outer edges blunt. This will prevent the catches 67 from holding back the bars 50 in case the ends should happen to strike against the edge of the recess 88 when these bars are moved toward the front and back of the framework 1 by the cams.

I wish to have it understood that the above description is illustrative only and discloses but one embodiment of my invention, and I do not care to be limited to the exact details shown and described, but wish to reserve to myself the right to make such changes in the shape, size and arrangement of the parts as fairly fall within the scope and spirit of my invention.

Having thus described my invention, I claim as new and desire to secure by Letters Patent:

1. In an improvement of the kind described, the combination of a sound-producing device, a pair of arms having knobs to engage said device, means for actuating the arms, a pair of hanger bars having projections to engage the arms and arrest the same, means for causing said arms and the projections thereon to be moved out of arresting position to permit the knobs to strike the device when required.

2. In an improvement of the kind described, the combination of a sound-producing device, a pair of arms having knobs to engage the same, means for actuating the knobs, a pair of hanger bars having means to engage the arms and arrest the same, means for pivotally mounting said hanger bars, counterweights attached thereto to hold said hanger bars in arresting position, means for engaging and swinging said hanger bars about their pivots and releasing the same, one of said bars being released before the other bar, whereby when the bars return to their starting position they will swing apart to allow the arms to strike the sound-producing device, means for arresting the other bar, and means for subsequently releasing the other bar to permit it to complete its return movement.

3. In an improvement of the kind described, the combination of a sound-producing device, a pair of arms having knobs to engage the same, means for actuating the knobs, a pair of hanger bars having means to engage the arms and arrest the same, means for pivotally mounting said hanger bars, counterweights attached thereto to

hold said hanger bars in arresting position, means for engaging and swinging said hanger bars about their pivots and releasing the same, one of said bars being released before 5 the other bar, whereby when the bars return to their starting position they will swing apart to allow the arms to strike the sound-producing device, means for arresting the other bar, means for subsequently releasing 10 the other bar to permit it to complete its return movement, and means for controlling the length of the period during which the knobs strike the engaging device.

4. In a clock, the combination of a sound-producing device, an arm having a knob to actuate the same, a pair of bars having means to engage the bar and arrest the same before the knob strikes the said device, one of said bars being released before the other, 15 and each of said bars being pivotally mounted and having counterweights to return the same to starting position, a catch carried by one of said bars, a cam for swinging said bars against the action of the counterweights and releasing the same, means to engage the catch to retard the movement of one of said bars and subsequently release the same to permit said bar to finish its return movement and again arrest the knob, and 20 means for regulating the releasing means to change the period during which the sound-producing device is actuated.

5. A clock, comprising a sounding member; a plurality of striking members; a continuously-operating mechanism for said striking members to normally actuate said striking members; a plurality of interceptors, each arranged to be moved into the path of one of said striking members; and a rotary disk for normally holding said interceptors removed from the path of said striking members.

6. A clock, comprising a sounding member; a plurality of striking members; a continuously-operating mechanism for said striking members to normally actuate said striking members; a plurality of interceptors, each arranged to be moved into the path of one of said striking members, one of 45 said interceptors being operatively connected with the driving mechanism of the minute hand of a clock to operate synchronously therewith, and the other of said interceptors being operatively connected to operate in 50 synchronism with the hour hand of said clock; and a plurality of rotary disks for holding said interceptors out of engagement with said striking members.

7. A clock, comprising a sounding member; a plurality of striking members; a continuously-operating mechanism for said

striking members to normally actuate said striking members; a plurality of interceptors, each arranged to be moved into the path of one of said striking members, one of said interceptors being operatively connected with the driving mechanism of the minute hand of a clock, to operate synchronously therewith, and the other of said interceptors being operatively connected to operate in 65 synchronism with the hour hand of said clock; a plurality of rotary disks for holding said interceptors out of engagement with said striking members; and means for varying the length of the operating portions of 70 said disks.

8. A clock, comprising a sounding member; a plurality of striking members; a continuously-operating mechanism for said striking members, to normally actuate said striking members; a plurality of interceptors, each arranged to be moved into the path of one of said striking members, one of said interceptors being operatively connected with the driving mechanism of the minute 85 hand of a clock, to operate synchronously therewith, and the other of said interceptors being operatively connected to operate in synchronism with the hour hand of said clock; a plurality of rotary disks for holding 90 said interceptors out of engagement with said striking members; and a movable section provided for said disks, to vary the length of the operating portion thereof.

9. A clock, comprising a sounding member; a plurality of striking members; a continuously-operating mechanism for said striking members, to normally actuate said striking members; a plurality of interceptors, each arranged to be moved into the path 95 of one of said striking members, one of said interceptors being operatively connected with the driving mechanism of the minute hand of a clock, to operate synchronously therewith, and the other of said interceptors being operatively connected to operate in 100 synchronism with the hour hand of said clock; a plurality of rotary disks for holding said interceptors out of engagement with said striking members; and a movable member mounted upon said disks, in a plane parallel therewith to provide a surface removed from the surfaces of said disks, said member being adapted to vary the operation 110 of said disks.

In testimony whereof I have signed my name to this specification in the presence of two subscribing witnesses.

BENJAMIN TRIVUS.
